PROCESS OF MANUFACTURING MOTOR FUEL

William E. Forney, Merchantville, N. J., assignor,
by mesne assignments, to Cities Service Oil
Company, New York, N. Y., a corporation of
Pennsylvania

Application February 19, 1936, Serial No. 64,671

4 Claims. (Cl. 196—10)

This invention relates to the manufacture of an improved motor fuel product and more particularly to a blending composition adapted to improve the anti-knock qualities of motor fuels or gasolines poor in this respect.

For a number of years past, the demand for high anti-knock motor fuels has been increasing and the petroleum refiner has been constantly improving the octane value of the gasolines produced. However, in almost every instance an improvement in the anti-knock character of the gasoline has resulted in the lowering of its end point. The higher boiling paraffin hydrocarbons have been found to have lower octane ratings than the lower boiling paraffin hydrocarbons. It has therefore been necessary to eliminate higher boiling fractions from the gasolines marketed because of the necessity of obtaining a certain specified octane rating.

The refining of cracked gasoline has also materially changed in recent years because of the necessity of avoiding the lowering of the octane rating of the gasoline through treating. Formerly it was the usual practice to refine cracked gasolines with concentrated sulfuric acid, but it is now a recognized fact that sulfuric acid treatment, particularly in the old type agitators, materially lowers the octane value of the resulting gasoline. Cracked gasolines are therefore now refined to a large extent by treating them with certain agents such as fuller's earth and similar adsorptive materials to avoid as far as possible the destruction of the desirable anti-knock constituents which in most cracked gasoline depends upon its content of unsaturated olefinic hydrocarbons.

The higher boiling hydrocarbon fraction however, which formerly went into the motor fuel product is now eliminated by a fractionating operation and either returned to the cracking unit or used as fuel oil.

The primary object therefore of the present invention is to provide a method of refining cracked gasolines in order to avoid the necessity of eliminating the heavier constituents which normally should be in the gasoline in order to give it a reasonably high B. t. u. value.

A further object of the invention is to provide a process for producing a gasoline motor fuel product having a relatively high end point and at the same time a higher octane rating than the crude gasoline as received from the cracking unit.

A still further object of the invention is to provide an improved blending material or frac-

tion of relatively high octane value suitable for blending with straight run gasoline or other relatively low octane motor fuel.

Accordingly the present invention relates to certain improvements designed to refine the crude cracked gasoline received from the cracking unit by bringing the same into intimate contact with concentrated phosphoric acid under such temperature and pressure conditions as to eliminate undesirable gum-forming constituents and at the same time actually increase the octane rating of the gasoline. The invention also includes the production of a relatively high octane blending product of high boiling point which is particularly adapted for blending with straight run gasoline or natural gasoline to increase the octane rating of the final blend. A further feature of the invention involves the contacting of unsaturated hydrocarbon gases with concentrated phosphoric acid under controlled temperature and pressure conditions to produce a polymerized product of unusual value as a motor fuel, or for blending with relatively low octane gasolines.

Other features and objects of the present invention will be apparent to those skilled in the art from the following more detailed description taken in connection with the accompanying drawing in which:

30 The single figure is a diagrammatic flow sheet showing a combination of apparatus elements particularly adapted for carrying out the improved process of the present invention to produce the improved product herein disclosed.

35 Referring to the drawing, the cracked gasoline to be refined is passed in vapor phase either directly from the cracking unit or from a vaporizing unit at a temperature of from 300° to 475° F. through a valved line 2 into a refining column 4 and passed upwardly therethrough in intimate contact with concentrated phosphoric acid. The column 4 may comprise the usual bubble cap tower of conventional design, in which the concentrated phosphoric acid flows downwardly over 40 the trays while the cracked hydrocarbon vapors pass upwardly in intimate contact with the phosphoric acid maintained in each tray. The concentrated phosphoric acid used in the tower 4 is introduced through a valved line 6, preferably 45 after being heated to a temperature equal to that of the incoming vapors. The refined gasoline vapors treated in the tower 4 are discharged through a vapor line 8 and conducted through one or more valved connecting lines 10, into the 50 lower mid-portion of a bubble plate fractionating

tower 12, in which the vapors are fractionated for the purpose of eliminating any undesired high boiling constituents and to give the gasoline the desired end boiling point according to market specifications.

The hot phosphoric acid which is preferably about 85% acid in passing downwardly through the treating column 4 polymerizes the extremely unsaturated hydrocarbons such as diolefines, as well as some of the normal olefines. The resulting polymers have been found to comprise not only the aliphatic hydrocarbons, but to include substantial proportions of naphthenic and aromatic hydrocarbons. The higher boiling polymers produced in column 4 are condensed and flow downwardly through the tower with the phosphoric acid. The phosphoric acid also reacts with olefines contained in the gasoline vapors to form certain amounts of alkyl phosphate compounds. The liquid mixture reaching the bottom of the tower 4 is withdrawn therefrom through a valved line 18 into a separator 16, in which the oil constituents are separated from the phosphoric acid and dissolved alkyl phosphates. If the acid mixture in the tower 4 should become too viscous because of the concentration of the phosphoric acid, a small proportion of steam may be introduced through the line 2. However, at the temperatures used in the tower 4, very little water is lost from the acid and in no case has the acid mixture been concentrated enough to affect its flow downwardly through the tower.

The partially spent phosphoric acid and dissolved alkyl phosphates are withdrawn from the separator 16 through a line 18 and all or any desired portion thereof may be withdrawn to storage through a valved line 20, or passed to a suitable apparatus for recovering the alkyl phosphates, or used for the manufacture of alcohols or other organic compounds. A portion of the partially spent acid withdrawn through the line 18 may be conducted through a line 22, a pump 24, and a valved line 26, which serve to reintroduce the partially spent acid back into the tower 4 through the line 6. The acid may be introduced into the mid-portion of the tower instead of the top of the tower by using the valve connecting line 28. Dilute recovered acid may be used in the top of the tower since the excess water will be removed with the vapor.

Certain gasolines may contain abnormally high proportions of unsaturated hydrocarbons or for some other reason may require a milder treatment than other gasolines. Therefore the phosphoric acid introduced through the line 6 may be modified by adding thereto some of the spent acid from separator 16. It has been found that alkyl phosphates (both the acid and the neutral phosphates) are very effective refining agents for certain types of cracked gasoline. By reintroducing these constituents into the top of the tower the refining agent in the tower 4 may be controlled very accurately. In the treatment of some gasolines, it is particularly desirable to give it a mild initial treatment in order to polymerize, react with, or stabilize very unstable compounds, and therefore provision is made for reintroducing the alkyl phosphates into the mid-portion of the tower 4 so as to independently control the composition of the treating material in the tower 4 and particularly in the lower half of the tower where it first contacts the fresh raw gasoline vapors.

The separator 16 may comprise any suitable

type of apparatus such as a gravity separator or a centrifugal separator. The partially spent acid and alkyl phosphates conducted through the lines 18 and 22 may be brought to any desired temperature for reintroduction into the column 4 by passing all or any portion thereof through a valved line 30 and conducting it through a heat exchanger 32 and back into the line 26. Ordinarily the acid passing through the line 30 may need to be heated in order to bring it to the desired temperature, but on the other hand, it may be cooled if for any reason the temperature of the acid discharged from the bottom of tower 4 has been heated too highly by the hot vapors introduced through the line 2.

The polymer oil separated out in the separator 16 which may comprise from 1% to 5% of the gasoline treated in the tower 4 is passed through a valved line 34 into a washer 36 in which the oil may be washed with water or an alkaline solution introduced through a valved line 38. An alkaline solution is preferred since it effectively removes any occluded acid constituents. The wash water or alkaline solution is withdrawn from the washer 36 through a valved line 40, while the refined oil is withdrawn through a line 42. This polymer oil withdrawn through the line 42 has been found to be a very unusual product because according to known practices it would have a relatively low octane rating and be entirely unsuited for use as a motor fuel. However, it was found on testing this product that it contained substantial proportions of aromatic hydrocarbons and that it had a relatively high octane value. In one particular instance, this polymer oil had a boiling range of from 310° to 486° F., a gravity of 34.7° A. P. I., and when blended in equal parts with Seminole straight run gasoline having an octane number of 50, it raised the octane number of the blend to 61.

The above described operation may be modified to the extent that hydrocarbon gases, preferably gases comprising principally propylene, the butylenes and pentenes, are introduced into column 4 through a line 44, and subjected to the treatment of phosphoric acid along with the gasoline vapors.

However, these and similar gases may be treated alone in column 4 with phosphoric acid, but the yield of polymer withdrawn with the phosphoric acid will be substantially lower. The contact of the unsaturated gaseous hydrocarbon with phosphoric acid and alkyl phosphates in column 4, particularly under pressures of from 250 to 350 pounds per square inch effects a substantial polymerization to normally liquid constituents containing appreciable quantities of aromatic and naphthenic hydrocarbons. Most of these normally liquid constituents however will remain in vapor state in the column 4 and pass through the lines 8 and 10 into the tower 12. The same thing is true in the treatment of cracked gasoline in column 4, since substantial polymerization of the lower molecular weight hydrocarbons in the gasoline increases the proportion of aromatic and naphthenic constituents which pass over with the vapors through the line 8. These results have been verified by the fact that the gasoline taken overhead through the line 8 has a substantially higher octane rating than the gasoline introduced into the tower 4 through the line 2. In a particular instance, it was noted that the aromatic hydrocarbon content of the gasoline treated in tower 4 had increased approximately 7%.

Where the gasoline constituents discharged from the column 4 through the line 8 have the proper end point desired for the gasoline, the use of the column 12 may be entirely dispensed with, but ordinarily the gasoline must be made for a particular market condition or for a particular season, so that in order to give it the proper desired end point it is subjected to fractionating in column 12. This column is provided with the usual bubble cap trays and with a steam heating coil 46 for maintaining the desired bottom temperature and temperature gradient in the column. The desired gasoline fraction is taken overhead from the column 12 through a vapor line 48 together with any uncondensable gases. This mixture is passed through a condenser 50 in which the gasoline is condensed and thereafter conducted through a line 52 to a receiver and gas separator 54. The uncondensable gases separated out are discharged from the receiver 54 through a valved line 56. In order to maintain the proper cut temperature on the column 12 a portion of the final product from the receiver 54 is withdrawn and passed through a line 58, a pump 60, and a line 62 onto the top tray in the column. The amount of such product returned to the column 12 may be automatically regulated in accordance with well-known practices. A pressure substantially equal to that in tower 4 may be held in tower 12 but 50 pounds is usually sufficient.

The final gasoline product recovered in receiver 54 is withdrawn through a valved line 64 into a washer 66 in which it is washed with water or alkaline solution introduced through a valved line 68. The spent solution is withdrawn from the washer through a valved line 70, while the final product is withdrawn through a valved line 72. This product may be sent directly to storage or market, or blended with some of the higher boiling products produced in the process by passing it through valved lines 74 or 74 and 76, which respectively discharge into blending tanks 78 and 80.

The heavy naphtha recovered in the base of the tower 12 is not returned to the cracking unit in accordance with the usual practice. It is a very valuable blending stock because of its relatively high content of naphthenic and aromatic hydrocarbons. It particularly contains substantial proportions of branched chain aliphatic and aromatic hydrocarbons which were produced in the column 4 by the action of the phosphoric acid. This heavy blending naphtha is withdrawn from the tower 12 through a valved line 82 and washed in a washer 84 with water or alkaline solution introduced through a valve line 86. The wash liquor is discharged through a valved line 88 while the finished heavy naphtha is discharged through a valved line 90. This product may be passed to storage and used directly as a motor fuel, or it may be introduced through valved connecting lines 92 and 94 respectively, into blending tanks 80 and 78.

In a similar manner the finished polymer product discharged from the washer 36 through the line 42 may be used as a heavy motor fuel or conducted through valved lines 96 or 96 and 98 respectively, into blending tanks 78 and 80. Straight run gasoline or natural gasoline may be introduced into the blending tanks 78 and 80 respectively through valved lines 100 and 102 to give the desired blends having the proper initial boiling point and octane number.

In the treatment of unsaturated hydrocarbon

gases such as cracking still gases and coke oven gases, a recovery of from 3 to 7 gallons of condensate per thousand cubic feet of gas is obtained, depending upon the unsaturated hydrocarbon content of the gas. Some of the material polymerizes to relatively high boiling constituents in the treating column 4, while the lower boiling polymers pass on to the column 12 and condenser 50. All of the liquid products obtained from the treatment of gases with the phosphoric acid in the tower 4 contain appreciable quantities of aromatic and naphthenic hydrocarbons. The gas discharged from the receiver 54 through the line 56 usually contains a relatively low proportion of unsaturated hydrocarbons, but the wet gases from the usual stabilizing apparatus where cracked gasolines are stabilized, have been found to give high yields when subjected to treatment in the tower 4.

As an example of the difference in character of untreated cracked gasoline and of the treated gasoline made in accordance with the process of the present invention, a cracked gasoline containing 18.2% unsaturates; 22.5% aromatics; 36.8% naphthenes; and 22.5% paraffins, when treated with phosphoric acid in accordance with the present invention showed an increase in the aromatic hydrocarbon content to 29.5% and a decrease in the unsaturates to 12.3%.

As a further example of the anti-knock character of the polymer product recovered from the tower 4 a vapor phase gasoline was treated in this column and the residue oil was recovered from the base of the column. This residue or polymer oil was redistilled and a heavy naphtha distillate having a gravity of 29.5 A. P. I., and a boiling range of 252° F. to 540° F. was recovered. This distillate was blended in equal proportions with a 350° F. end point straight run Pennsylvania gasoline of 51 octane number (by C. F. R. motor method). The resulting blend by the same test engine had an octane number of 63.7.

In the treatment of cracked gasolines in the tower 4, it is unnecessary to use high pressures, but pressures of approximately 50 lbs. have given satisfactory results. In the treatment of unsaturated hydrocarbon gases however, a high pressure of from 250 to 350 lbs. per square inch gives a longer time reaction and facilitates the polymerization or reactions taking place in the tower 4. The term "polymerization" may not accurately define the reactions taking place between the unsaturated hydrocarbons and the phosphoric acid, because it is undoubtedly true that the acid enters into the reaction in many instances to form an intermediate product which in the presence of other unsaturated hydrocarbons produces constituents such as naphthenes, branched chain aliphatic and aromatic hydrocarbons, and other products which have superior anti-knock properties.

The reactions carried out in the tower 4 may be effected in the liquid phase by suitably adjusting the temperature and pressure relationship of the constituents introduced thereto through the lines 2 and 44. In this case only the very heavy hydrocarbons which may dissolve in the acid mixture will be carried out through the line 14. Practically all of the liquid hydrocarbons will be carried overhead through the line 8 into the tower 12 in which the very heavy constituents used to make up the heavy blending stock will be separated and withdrawn through the line 82.

From the foregoing description of the present invention, it is apparent that certain modi-

fications may be made in the operation without departing from the scope thereof. For example, the blended products formed in the blending tanks 78 and 80 may be varied to suit particular conditions, according to the demands of the market or the particular motor in which the fuel is to be used. In any case, it is apparent that considerable advantage is obtained from the process and that normally waste products or substantially valueless products are converted into products of superior quality.

Having thus described the invention in its preferred form, what is claimed as new is:

1. The process of manufacturing a high anti-knock motor fuel product which comprises 15 passing a hydrocarbon mixture containing substantial proportions of unsaturated olefinic hydrocarbons through a zone in intimate contact with phosphoric acid, maintaining a temperature of approximately 375° F. in said zone and a superatmospheric pressure whereby portions of said hydrocarbons are converted into constituents condensable under the conditions obtaining in said zone, withdrawing a liquid oily product formed in said zone therefrom and washing the same to remove any acidic constituents, and blending the resulting washed oil with a low octane motor fuel to substantially increase the octane rating of the low octane motor fuel.

2. The process defined by claim 1 in which the said hydrocarbon mixture is passed in intimate contact with phosphoric acid and a substantial proportion of alkyl phosphates.

5 3. The process defined by claim 1 in which said mixture of hydrocarbons includes normally gaseous unsaturated hydrocarbons.

4. The process of manufacturing a blending stock of high anti-knock properties for blending 10 with poor gasolines, which comprises passing gasoline hydrocarbons containing a substantial proportion of unsaturated olefinic and aromatic constituents together with a mixture of normally gaseous olefinic hydrocarbons in intimate contact with concentrated phosphoric acid maintained at a temperature of approximately from 300° to 475° F. in a reaction zone whereby a liquefied polymer oil product is formed, discharging the treated gasoline vapors from said reaction zone as a refined gasoline product, withdrawing said liquefied product from said reaction zone and washing the same with an alkaline solution to produce said blending stock, and blending the same with a gasoline motor fuel 20 having an octane number of approximately 50 in a proportion sufficient to provide a blended product having an octane number in excess of 60.

WILLIAM E. FORNEY.
